UNITED STATES PATENT OFFICE.

JAMES A. ST. JOHN, OF ST. LOUIS, MISSOURI.

DESIGN FOR MOVABLE TYPE.

SPECIFICATION forming part of Design No. 14,011, dated June 26, 1883.
Application filed March 27, 1883. Term of patent 3½ years.

To all whom it may concern:

Be it known that I, JAMES A. ST. JOHN, a subject of the Queen of Great Britain, residing in the city of St. Louis, Missouri, have invented and produced a new and original Design for Movable Type, of which the following is a full, clear, and exact description, reference being had to the accompanying impression, forming part thereof.

10 The characteristics of the present font of type are the inclined quadrilateral form of the various characters; an outline of uniform width; fineness of outline; absence of shading. The first-named characteristic has reference to 15 the general form of the entire space occupied by most of the letters and numerals—for instance, the letters G E O C S, upper-case, and the letters a c m n o, lower-case; and also to the

general form of the body of several of the letters—for instance, the letters P J, upper-case, and the letters b d f, lower-case. The fine uniform outline is observable in all the characters.

I claim—

1. The design for movable type herein shown and described, the same consisting in the inclined quadrilateral form.
2. The design for movable type herein shown and described, the same consisting in the inclined quadrilateral form and the fine uniform outline, in combination.

JAMES A. ST. JOHN.
